G. D. BUCK.
COMBINED PUMP AND FIRE EXTINGUISHER.
APPLICATION FILED JULY 23, 1917.

1,256,870.

Patented Feb. 19, 1918.

UNITED STATES PATENT OFFICE.

GEORGE D. BUCK, OF ST. LOUIS, MISSOURI.

COMBINED PUMP AND FIRE-EXTINGUISHER.

Specification of Letters Patent. Patented Feb. 19, 1918.

1,256,870.

Application filed July 23, 1917. Serial No. 182,208.

To all whom it may concern:

Be it known that I, GEORGE D. BUCK, a citizen of the United States, a resident of the city of St. Louis, in the State of Missouri, have invented certain new and useful improvements in Combined Pumps and Fire-Extinguishers, of which the following is a full, clear, and exact description, reference being had to the accompanying drawings, forming a part of this specification.

My invention relates to a combined pump and fire extinguisher. The new device can be used as an ordinary pump for inflating pneumatic tires and the like, and it can also be used as a fire extinguisher. In accordance with the present invention, an ordinary tire pump can, at a very small cost, be converted into a highly efficient fire extinguisher, without in any way impairing the usefulness of the tire pump. To accomplish this, a chemical cylinder is associated with the pump in such a manner that it will not interfere with the flow of air from the pump to a tire. By operating a simple valve device, the air can be directed from the pump cylinder to the chemical cylinder, and in this event the air pressure will be transmitted from the pump to the fire extinguisher. In addition to the broad disclosure of a combined pump and fire extinguisher, I have herein shown and described a specific combination and arrangement of elements which coöperate with each other to constitute a simple unitary structure, well adapted to perform either of its two functions. To produce a complete fire extinguisher, the pump must coöperate with the chemical cylinder, and owing to the manner in which the various elements are combined with each other, the general efficiency of the device as tire pump is not affected by the chemical cylinder.

Figure I is a front elevation of a combined pump and fire extinguisher constructed in accordance with my invention.

Fig. II is a side elevation.

Fig. III is a transverse section on line III-III, Fig. I.

Fig. IV is an enlarged detail view, partly in section, showing the 3-way valve.

Fig. V is an enlarged fragmentary view of the upper portion of the chemical cylinder.

To illustrate the invention, I have shown a tire pump comprising a low pressure cylin-

der 1, a high pressure cylinder 2, a base 3 to which the lower ends of the cylinders are secured, a head 4 secured to the upper ends of the cylinders, pistons 5 arranged in the cylinders, piston rods 6 secured to the pistons and extending through the head 4, and an operating handle secured to the upper ends of the piston rods. The air forced from the bottom of the cylinder 1 flows through a passageway 3' in the base 3, and enters the lower end of cylinder 2.

The air under pressure, discharged from the outlet at the upper end of the cylinder 2, passes through a valve housing 8 and also through the usual flexible tube 9, which I will term the main air conductor. This air conductor is secured by means of a coupling 10 to the valve housing 8, and it is provided at its lower end with the usual coupling 11 adapted to be attached to a pneumatic tire. When the device is used as a tire inflating pump, the air under pressure flows from the pump cylinders and through the flexible tube 9 in the usual manner.

12 designates an elongated chemical cylinder arranged parallel with the pump cylinders and secured thereto by means of bands 13 which surround all of the cylinders. A secondary air conductor 14 leads from the valve housing 8 to the upper end of the chemical cylinder 12, and a check valve 15 (Fig. V) is arranged in said secondary conductor to prevent chemicals from flowing from the chemical cylinder to the valve 90 housing 8. A discharge member 16, at the lower end of the chemical cylinder, is provided with a valve 16', for controlling the escape of fluid from said cylinder. 17 designates a 3-way valve arranged in the valve 95 housing 8 (Fig. IV), the latter being provided with three passageways adapted to be opened and closed by the valve.

When the device is used as an ordinary tire pump, the 3-way valve occupies the position shown in Fig. IV, and the air under pressure can then flow freely from the pump cylinders to the main conductor 9, which leads to the tire. When used as a fire extinguisher the 3-way valve is adjusted to 100 close communication between the pump and the main conductor 9, at the same time placing the pump in communication with the secondary conductor 14 leading to the chemical cylinder. The air under pressure 105 is then forced into one end of the chemical

cylinder, and the fire extinguishing medium is discharged through the valve 16' at the bottom of the chemical cylinder.

The pump operating handle and the valve 16' lie at opposite ends of the structure, so the device can be conveniently handled when used as a fire extinguisher. It will be observed that I have produced a highly efficient fire extinguisher by merely adding a few simple and inexpensive elements to an ordinary hand pump, and these elements are so combined with the elements of the pump that the new device can be easily and quickly converted from a tire pump to a fire extinguisher by merely turning the valves 16' and 17.

I claim:

1. In a combined tire pump and fire extinguisher, a hand-pump provided with an outlet and a main conductor for the discharge of air under pressure, a chemical cylinder secured to said pump and communicating with said outlet, means under the control of the operator whereby the air under pressure passing from the pump can be directed either to said main conductor or to said chemical cylinder, the pump operating handle being located at one end of the device, and a discharge member secured to the chemical cylinder near the opposite end of the device.
2. In a combined air pump and fire extinguisher, a pump provided with an outlet for the air under pressure, a main air conductor leading from said outlet, a secondary conductor branching from said main air conductor, selective means for controlling the flow of air from the pump to either of said conductors, a chemical chamber communicating with said secondary conductor, and a valve for controlling the escape of fluid from said chemical chamber.
3. In a combined tire pump and fire extinguisher, a pump cylinder provided with an outlet for the air under pressure, a piston

in said cylinder, an operating handle connected to said piston, a flexible tube for conducting the air under pressure to a tire, a secondary air conductor leading from said pump, a chemical cylinder associated with 50 and secured to said pump cylinder, said cylinders being approximately parallel with each other and said chemical cylinder being in communication with said secondary air conductor, selective means whereby the air 55 passing from said pump may be directed either to said flexible tube or to said secondary air conductor, and a valve for controlling the escape of fluid from said chemical cylinder.

4. In a combined tire pump and fire extinguisher, a vertical pump cylinder provided with an outlet for the air under pressure, a piston in said pump cylinder, an operating handle arranged above said pump 65 cylinder and secured to said piston, a three-way valve housing communicating with said outlet, a flexible discharge tube coupled to said three-way valve housing, a secondary air conductor leading from said three-way valve 70 housing, a three-way valve arranged in said valve housing so as to direct the air either to said flexible discharge tube or to said secondary air conductor, a chemical cylinder associated with and secured to said pump 75 cylinder, said cylinders being approximately parallel with each other, the discharge end of said secondary conductor being connected to and in communication with the upper end of said chemical cylinder, a check valve associated with the secondary conductor to prevent the flow of fluid from the chemical cylinder to said three-way valve, a discharge member at the bottom of said chemical cylinder, and a valve for controlling the 80 flow of fluid through said discharge member.

In testimony that I claim the foregoing I hereunto affix my signature.

GEORGE D. BUCK.
